SMOKING PIPE

Stephen P. Chernock, 1553 Boston Post Road,
Milford, Conn. 06460

Filed May 29, 1967, Ser. No. 7,284

Term of patent 14 years

(Cl. D85—8)

Fig. 4.

Fig. 1.

Fig. 2.

Fig. 3.

Fig. 5.

Fig. 6.

FIGURE 1 is a top plan view of a smoking pipe, showing my new design;

FIGURE 2 is a side elevational view;

FIGURE 3 is a bottom plan view;

FIGURE 4 is a front elevational view;

FIGURE 5 is a transverse sectional view, taken along the line 5—5 of FIGURE 2; and

FIGURE 6 is a transverse sectional view, taken along the line 6—6 of FIGURE 2.

The dominant features of the design reside in the portions shown in full lines.

The dominant feature of my design resides in the full length rib on the upper side of the shank member in combination with longitudinally spaced tooth-like fins projecting laterally at opposite sides of said shank member having their upper surfaces inclined upwardly and outwardly from the side edges of said rib to provide longitudi-

nal grooves at each side of the rib, and an extension of said rib disposed along a portion of the upper side of the mouthpiece having side edges which converge to a point spaced from the tip of the mouthpiece.

I claim:

The ornamental design for a smoking pipe, substantially as shown and described.
